TORCH

Louis V. Aronson, Newark, N. J., assignor to Art Metal Works, Inc., Newark, N. J., a corporation of New Jersey

Application February 19, 1935, Serial No. 7,273

5 Claims. (Cl. 67—7.1)

The invention relates to torches for igniters, particularly for igniters utilizing pyrophoric material.

It is an object of the invention to provide a torch having means to feed wicking to a position to support a flame.

It is a further object of the invention to provide a torch adapted for use with a striker type of ignition device having a feed for the wicking which may be operated by revolution of a member coaxial with the torch.

It is a further object of the invention to provide a torch having a tubular element revolvably associated with a handle desirably shaped to simulate an ornamental end of a pencil by which the torch may be withdrawn from a fuel reservoir, and constructed and arranged for feed of the wick of the torch by revolution of the handle.

Further objects of the invention will appear from the following description when read in connection with the accompanying drawing showing an illustrative embodiment of the invention, and wherein:

Figure 1 is an exploded perspective view of the portions of the torch exclusive of the wicking;

Figure 2 is a central vertical section showing a portion of a fuel reservoir in section; and

Figs. 3 and 4 are transverse sections on lines 3—3 and 4—4 respectively of Figure 2.

The device as illustrated is particularly designed for use with a cigar or cigarette lighter wherein the fuel reservoir may be a portion of the casing of a mechanical pencil.

The torch itself comprises a tubular element 11 and a handle member 12 which, as shown, simulates the ornamental end of a pencil. The handle 12 is shown as formed with a socket 13 having a screwthreaded opening 14. The socket 13 is of a size to receive a collar 15 carried by the tube 11 and the tube 11 may be revolvably retained in the socket 13 by means of a locking bushing 16 screwthreaded for engagement with the screwthreads 14.

The bushing 16 is shown as formed with an annular lip 17 to seat upon the end of the reservoir 18 and with a tapered portion 18 to fit into the opening in the reservoir whereby it may be withdrawn therefrom by a straight pull.

Secured in the handle 12 there is shown a non-circular rod 19, desirably formed square in cross section, which rod extends coaxially through the tube 11 projecting as at 20 to provide a striker element for coaction with pyrophoric material.

To support a flame caused by ignition of fuel and to carry said fuel, there is shown a mass of

absorbent material 21 which may be a fibrous wicking and which projects at 22 from the lower end of the tube around the rod 19.

To feed the wicking to adjust the amount of its exposure, the tube 11 is shown as formed with a screw-threaded portion 23 with which the wicking engages in such manner that when the rod 19 is revolved by turning the handle 12, while holding the tube 11 stationary, the mass of wicking will be caused to revolve in contact with the screw-threads 23 and therefore to feed the wicking out of or into the tube 11.

The wicking 21 being first placed into the tube 11 and the rod 19 then forced down the center of the mass will result in wedging the wicking out 15 into contact with the threads 23 so as to compress the wicking into the threads whereby the feeding action will result from revolution of the wicking by rotation of the rod.

Since the rotation of the handle 12 is depended upon for feed of the wicking, it becomes important to be able to withdraw the torch from the fuel reservoir by a straight pull instead of by unscrewing a threaded engagement and therefore the tapered portion 18 of the locking bushing 16 becomes desirable.

In devices of this character the flame supporting portion of the wicking rapidly becomes consumed, particularly when the fuel supply in the reservoir is depleted and it is a distinct advantage to be able to adjust the amount of exposure of the wicking to preserve the usefulness of the torch over considerable periods of time.

Minor changes may be made in the physical embodiment of the invention within the scope of the appended claims without departing from the spirit thereof.

I claim:

1. An ignition torch comprising, in combination: a tubular element; a mass of absorbent material in and exposed at an end of said element; a rod element housed in and coaxial with said tubular element extending lengthwise of said mass of absorbent material and projecting therefrom to provide a striker member to coact with pyrophoric material; one of said elements formed with a screw-threaded portion; and means whereby relative rotation between said elements feeds said absorbent material to exposure.

2. An ignition torch comprising, in combination: a tubular element; a mass of absorbent material in and exposed at an end of said element; a rod element housed in said tubular element coaxial therewith, rotatable relative

thereto, extending lengthwise within said mass of absorbent material and projecting therefrom to provide a striker member to coact with pyrophoric material; a screwthreaded portion carried by one of said elements in engagement with said mass of absorbent material and a non-cylindrical surface formed on the remaining element in engagement with said mass; whereby relative rotation of one of said elements with respect to the 10 remaining element will cause rotation of said mass relative to said screwthreads for adjustment of said exposure.

3. An ignition torch comprising, in combination: a tubular element internally screwthreaded for at least a portion of its length; a handle member rotatably engaging said element; a non-cylindrical rod fixedly carried by said member and projecting axially in said element; a mass of absorbent material surrounding said rod within 15 said element, in engagement with said screwthreads and exposed at an open end of said element; whereby rotation of said rod by causing rotation of said absorbent material will adjust the exposure thereof.

4. An ignition torch comprising, in combination: a tubular element having an interior screwthreaded portion; a collar upon an end of said element; a handle having a socket receiving said collar and the end of said element; a bushing having screwthreaded engagement with the wall of said socket to retain said collar; a non-cylindrical rod secured to said handle projecting through said tube to provide a striking end; and a mass of wick material surrounding said rod and 10 in engagement with said interior screwthreads and projecting from the tubular element about said rod. 5

5. An ignition torch comprising, in combination: a tubular element; a mass of wicking in 15 said element; a handle revolvably mounted on said element; means whereby revolution of the handle relative to the element feeds the wicking to exposure at an open end of the element; and a bushing carried by and revoluble with said handle to engage and disengage an opening in a fuel reservoir by purely rectilinear movement. 20
